UNITED STATES PATENT OFFICE.

LEONIDAS R. HOUCHENS, OF FAIRFAX, VIRGINIA.

PROCESS OF PRESERVING A CORPSE.

Specification of Letters Patent. Patented Apr. 18, 1916.

1,179,526.

Application filed July 21, 1915. Serial No. 41,068.

To all whom it may concern:

Be it known that I, LEONIDAS R. HOUCHENS, citizen of the United States, residing at Fairfax, in the county of Fairfax and State 5 of Virginia, have invented certain new and useful Improvements in Processes of Preserving a Corpse, of which the following is a specification.

This invention relates to burial caskets especially adapted for the preservation of 10 corpses; and the improvement is particularly designed for use on shipboard for preserving bodies in good condition for burial upon the completion of a voyage.

15 While the invention is primarily intended for the use above stated, its utility of course obviously is not restricted to such use, but is adapted for service wherever it is desirable to preserve a body within a casket.

20 The invention comprises a casket of novel construction, a container for chemicals or preserving liquid connected with the casket, a pump for withdrawing fumes from the casket and valves for the inlet and outlet of 25 liquid therefrom.

The construction of the casket will be fully described hereinafter in connection with the accompanying drawing which constitutes a part of the specification, and its 30 features of novelty will be set forth and defined in the appended claim.

In the drawing, Figure 1 is a central vertical section of a burial casket and preserving apparatus, embodying the invention. 35 Fig. 2 is a top plan view of the same, and Fig. 3 is a detail sectional view showing the discharge spout for withdrawing the insulating material or filling supplied to the space between the outer sides of the casket 40 walls, and the depending flange of the casket cover.

The casket consists of a bottom 1, sides 2 and ends 3 and 4.

The ends and sides of the casket are 45 closed by a flanged jacket 5, which provides a space 6 entirely surrounding the upper portion of the structure, and this space is adapted to contain any suitable filling for

sealing the cover upon the casket hermetically. 50

At one end of the casket the jacket projects outward as at 7 and is provided with a filling tube or funnel 8.

The reference numeral 9 designates the casket lid or cover preferably provided with 55 a glass plate 10, and having a continuous depending flange 11 fitting down within the space 6 and adapted to be sealed therein by a cementitious filling 12. The lid or cover 9 is also provided with a suitable valve 13 60 for admitting oxygen to the casket when desired.

In connection with the casket constructed as thus described, I employ a liquid container 14 containing an air-pipe 15, extending through its cover 16, the latter having an opening for the attachment of a rubber tube or hose 17, the other end of which is connected to a valve casing 18 projecting from the end 4 of the casket, and containing 70 a valve for controlling the supply of liquid from the container 13 to the interior of the casket where the body is exposed to its preservative action. It will be noted that I thus secure an embalming or preserving action 75 on the body without any touching or handling of the body as is necessary in the ordinary embalming treatment.

To provide for the escape of fumes from the casket, the latter is equipped with a discharge spout 19 connected to a pump barrel 20 having a discharge nipple 21, and containing a suction piston, mounted upon a rod having a handle 22. If desired, a rubber tube (not shown) may be attached to 85 the nipple 21 to convey the discharge to a distance away from the casket.

If desired, guard-pipes 23 may be provided upon the inner sides of the ends of the casket over the inlet and outlet openings 90 therein.

An outlet 24 closed by a valve 25 is provided for the filling space 6.

The operation and utility of the improvement will be readily understood. 95

Preserving liquid is admitted to the cas-

ket in contact with the body, without liability of escape, except by the discharge means provided; and bodies thus treated may be preserved in good condition for long periods, the hermetic sealing of the casket effecting this result.

Having fully described my invention, what I claim is:

The process of preserving a corpse which

consists in placing the body in a permanent casket having a cover adapted to be hermetically sealed, sealing said cover, withdrawing the air from the casket, supplying antiseptic gas to replace the air, and then permanently sealing the casket.

In testimony whereof I affix my signature.

LEONIDAS R. HOUCHENS.
